UNITED STATES PATENT OFFICE.

CHESTER I. WAGNER, OF DAYTON, OHIO.

FILING-FOLDER.

1,175,209.

Specification of Letters Patent. Patented Mar. 14, 1916.

Application filed March 19, 1913. Serial No. 755,299.

To all whom it may concern:

Be it known that I, CHESTER I. WAGNER, a citizen of the United States, residing at Dayton, in the county of Montgomery and State of Ohio, have invented a new and useful Filing-Folder, of which the following is a specification.

My invention relates to means for securing correspondence or other papers in filing 10 folders, and among its objects are the following:—First—to provide a holder on which papers may be hooked with practically the same facility as they are hung on the ordinary pin file. Second—to provide a 15 holder such that the papers may be divided at any point, the top ones thrown over the top of the folder, entirely exposing the next paper and permitting its removal from the folder, if desired. Third—to make the 20 holder so that the space it occupies between the wings of the folder will be substantially proportioned to the number of papers the folder contains. The advantages derived from these features, and other advantages, 25 will become manifest as I proceed with the description.

In the accompanying drawings Figure 1 shows a portion of a folder equipped with my improved holder. Figs. 2, 3 and 4 show 30 steps in the operation of putting a paper on the holder. Figs. 5 and 6 illustrate the manner of manipulating a paper in carrying it across the opening. Figs. 7 and 8 show a modified construction of the ring. Fig. 9 shows another modification. Figs. 10 and 35 11 each show a construction in which the rings are connected by a link. Fig. 12 is a detail illustrating the manner of constructing the rings shown in Figs. 1 to 6, and 40 Fig. 13 shows a modified construction for the ring.

Similar numerals refer to similar parts throughout the several views.

Referring more particularly to Fig. 1, 25 45 is an ordinary paper filing folder—ordinary in the sense that it may be made any desired size and of any of the materials usually employed for such purposes. At the top of one wing of the folder the paper holders, 50 the rings 26, are flexibly mounted or carried by strips of metal 27. Each strip is formed around the body of the ring, one end of the strip is then passed through a

slit in the folder and its ends riveted together by rivets 28. To give greater rigidity 55 the lower portion of one strip and the upper portion of the other is extended and the two strips are united by the rivet 29. An aperture 30 is made in the part of each strip which encircles the ring, through which the 60 tongue 31 of the ring passes, one edge of each aperture, the one at the right of the rings in Fig. 1 being so situated that it acts as a stop to prevent the ring swinging beyond a certain point in that direction. The 65 opposite edge is cut away to allow movement of the tongue. See Fig. 12. It will be noted that the stops act upon the same side of each ring and prevent the rings swinging past a position perpendicular to 70 the folder. From this position the rings may swing or fall over and lie flat against the folder.

In Figs. 2, 3 and 4, 35 represents a sheet of paper being hung on a ring, the paper 75 having been previously perforated at 36. The edge of the paper is inserted between the overlapping juxtaposed ends 37 and 38, the ends being separated by a sufficient space to admit the paper freely. Fig. 2 shows the 80 end 37 about to enter the hole 36 in the paper; Fig. 3 shows the paper about to pass from between the ends; and Fig. 4 shows the paper in place on the ring. In Fig. 5 the manner of manipulating the paper when it 85 is to be thrown back to expose the paper below is indicated by the arrows. By drawing the paper slightly toward the axis of the ring it will carry across the opening without catching on the inner end. Fig. 6 90 shows the manner of holding the paper to return it. A bunch of papers can be carried back and forth in the same manner, and if desired, a particular one may be removed from the folder without removing 95 those above it. All that is necessary is to throw the papers above the one wanted over the top of the folder. The next paper can be removed by drawing it outward and toward the top of the folder.

The rings shown in Figs. 1 to 6 and in Fig. 12 are made of a single piece of wire doubled back upon itself so as to bring the ends of the wire opposite the opening, where they are bent inward to form the tongue 31. 105 Fig. 8 shows a ring in which the ends of

the wire overlap to form the opening, and a member 41 is formed by a loop in the wire. In this ring the ends of the wire are rounded off and each is bent slightly toward the adjacent end to avoid exposed sharp corners which might tear the papers. In Figs. 9 and 13 the ends of the wire are beveled for the same reason, and in Fig. 9 the offset is omitted in the end 37. This ring is also 10 different from the others in that the lower portion is rectangular.

Fig. 10 shows a method of connecting the rings so they will move in unison, the link 40 being connected to the members 41. 15 When so arranged the coöperation of the aperture 30 and tongue is not necessary, the ends of the link engaging the strip 27 and limiting the movement of the rings. In Fig. 11 the member 42, though constructed differently, serves the same purpose as member 41 in Figs. 8, 9 and 13. Connecting the rings by the link has two objects, both of which, however, are capable of attainment by other means. The first of these is that, 20 assuming the folder lies on a table or the like, the weight of the link tends to keep the rings in their upright positions while papers are being filed, and, second, it insures the links being the correct distance apart, thereby facilitating the filing operation. After a number of papers have been filed the papers themselves perform practically the same function as the link. Arranging the rings to fall away from the fold of the 25 folder renders their action substantially automatic, at least in one direction, and it is obvious that the angle of the rings; *i. e.*, the amount of space they will occupy when the folder is closed will be approximately 30 proportional to the number of papers the folder contains.

While the use of filing folders is increasing rapidly the lack of a simple, cheap and effective means of holding papers in the 45 folders has always been and is now regarded as a defect in the system, and my holder is designed to supply this deficiency. But its sphere of usefulness is not confined to folders, since it may be used to hold papers in binders as well. For this and other uses 50 minor modifications may be made without departing from the substance or exceeding the scope of the appended claims.

What I claim is as follows:—

- 55 1. A paper holder comprising a ring made of a single piece of wire having juxtaposed but separated overlapping ends, said ends having rounded contours to avoid abrading or puncturing the paper.
- 60 2. A paper holder comprising a ring made of a piece of wire which is longer than the circumference of the ring, the excess wire being made to over-lap a portion of the ring; said overlapping portion being concentric to but separated from the part it

over-laps by a substantial distance, and of the same size and form as the remainder of the wire.

3. A paper holder comprising a wire ring having juxtaposed but separated overlapping ends, one of said ends being offset to permit of its lying outside of the other end. 70

4. A paper holder comprising a ring made of a piece of wire which is longer than the circumference of the ring, the excess wire being made to form a portion of a ring of larger diameter than the first, said portion being outside of and concentric to the first ring but separated therefrom by a substantial space. 75

5. A paper holder comprising a ring made of a piece of wire which is longer than the circumference of the ring, the excess wire being made to form a portion of a ring of larger diameter than the first, said portion being outside of and concentric to the first ring but separated therefrom by a substantial space, the concentric portion of the wire being of the same size and form as the remainder thereof. 80

6. A filing folder having two paper holders, each being a ring having an opening for the reception of papers, said openings being approximately perpendicular to the plane of a paper which is hung in the ring; 90 the rings being flexibly mounted in the folder by means which limits their movement to approximately ninety degrees, one extremity of said movement being perpendicular to the folder, the movement of the 100 rings from said perpendicular position being in the same direction.

7. In a file the combination of a folder, a ring having an opening for the reception of papers and having a tongue approximately opposite the opening, and a strip of sheet metal bent around the body of the ring, the strip having an aperture through which the tongue passes, one end of the strip being passed through a slit in the 110 folder and its ends riveted together with the folder interposed, the tongue coöperating with one side of the aperture to prevent the ring moving in one direction beyond a position perpendicular to the folder. 115

8. A file comprising a folder having two wire rings, each having juxtaposed but separated overlapping ends, said rings being flexibly mounted upon the folder, and means for limiting the movement of each ring to 120 approximately ninety degrees, one extremity of said movement being perpendicular to the folder, the movement of both rings from said perpendicular position being in the same direction.

9. A file comprising a folder having two wire rings, each having juxtaposed but separated overlapping ends, said rings being flexibly mounted upon the folder, thereby permitting them to assume a position per- 130

pendicular to the folder or to fall over toward the folder, and means whereby the rings can fall only one way from the perpendicular position, both rings falling in the same direction.

10. A file comprising a folder having two wire rings, each having an opening for the reception of papers, said rings being flexibly mounted upon one wing of the folder, and means whereby when the rings swing in their mountings they are made to move in unison.

11. A file comprising a folder having two wire rings, each having an opening for the reception of papers, said rings being flexibly mounted upon one wing of the folder, means whereby when the links move in their mountings they are made to move in unison, and means for limiting the movement of the rings to approximately ninety degrees.

12. A file comprising a holder having two wire rings, each having juxtaposed but separated overlapping ends and a projecting tongue, said rings being flexibly mounted

upon one wing of the folder and a link 25 whose ends are flexibly connected to the tongues of the rings, whereby when the rings swing in their mountings they are made to move in unison.

13. In a filing folder the combination of 30 two paper holders, each being a ring having a permanent opening for the reception of papers, the rings being flexibly mounted in the folder by means which limits their movement to approximately ninety degrees, 35 one extremity of the movement being approximately perpendicular to the folder; means whereby the movement of both rings from said perpendicular position is in the same direction, and means for keeping the 40 openings in the rings in a fixed position with reference to, preferably opposite, their points of attachment to the folder.

CHESTER I. WAGNER.
